CLAIM

The ornamental design for a device holder and stand, as shown and described.

DESCRIPTION

FIG. 1 is a top front perspective view of a device holder and stand according to the design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof;

FIG. 8 is a top front perspective view of the device holder and the stand shown detached for clarity of illustration; and, FIG. 9 is a bottom front perspective view of FIG. 8.

The long-dash-short-dash lines form an unclaimed boundary.

In the drawings, portions of the device holder shown by broken lines do not form part of the claimed design. The device holder and stand are shown with break lines. The appearance of any portion of the device holder and stand between the pair of break lines forms no part of the claimed design.
